United States Patent

Des. 241,198
Patented Aug. 31, 1976

241,198

STORAGE UNIT FOR BATHROOMS OR THE LIKE

Albert L. Busch, La Puente, Calif., and Marilyn Thompson, 2212 El Monte Ave., Arcadia, Calif. 91006, administratrix of said Albert L. Busch, deceased

Filed Nov. 21, 1974, Ser. No. 525,933

Term of patent 14 years

Int. Cl. D6—04; D23—02
U.S. Cl. D6—86

Fig. 2.

Fig. 3.

Fig. 1.

Fig. 4.

FIG. 1 is a front elevational view of a storage unit for bathrooms or the like showing my new design, with the broken line disclosure showing a portion of a wall, floor, bathtub, and a companion unit for illustrative purposes only;

FIG. 2 is a top plan view thereof;

FIG. 3 is a front perspective view thereof; and

FIG. 4 is a rear perspective view thereof.

I claim:

The ornamental design for a storage unit for bathrooms or the like, substantially as shown and described.
